UNITED STATES PATENT OFFICE.

HOVSEP H. ASADOORIAN, OF TROY, NEW YORK.

THREAD CUTTER AND HOLDER FOR BUTTONHOLE-SEWING MACHINES.

1,133,605.

Specification of Letters Patent. Patented Mar. 30, 1915.

Application filed September 25, 1912. Serial No. 722,214.

To all whom it may concern:

Be it known that I, HOVSEP H. ASADOORIAN, a citizen of the United States, residing at Troy, county of Rensselaer, and State of New York, have invented certain new and useful Improvements in Thread Cutters and Holders for Buttonhole-Sewing Machines, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a top plan view of part of a Reece button-hole-sewing machine showing my thread-cutting and holding attachment thereon. Fig. 2 is a side elevation of the same. Fig. 3 is a view corresponding with a part of Fig. 2 showing a different position of the movable parts. Fig. 4 is a view corresponding with a part of Fig. 1 with the movable parts in different positions. Fig. 5 is a view in front-end elevation of the parts shown in Fig. 4. Fig. 6 is a view in perspective of the cutter-releasing arm detached. Fig. 7 is a view in perspective of the cutter-opening arm detached. Fig. 8 is a vertical cross section taken on the broken line 8—8 in Fig. 4.

The principal object of the invention is to cut and hold the thread upon completion of the operation of stitching a button-hole.

My attachment made with proper modifications may be applied to different button-hole-sewing machines; but it is especially adapted for use in connection with a button-hole-sewing machine of the Reece type, the general structure of which is shown in Letters Patent No. 462,865, granted Nov. 10, 1891, to G. S. Hill. In a machine of this type, the stitch-forming mechanism, throat-plate and buttonhole-cutter are mounted upon a frame which has a reciprocating movement relatively to the work-clamp and bed of the machine in the direction of the length of the buttonhole. When the operation of stitching the buttonhole is completed, said movable frame moves forward to the position in which the cutter operates, and when in this position, the needle-bar and throat-plate are rotated in one direction, and before the stitching of the next button-

hole is begun, said needle-bar and throat-plate are reversely rotated. Also in said type of machine, the shaft which operates the needle is driven by means of a clutch from the shaft which moves said frame, and which operates the cutter and rotates the needle-bar and throat-plate, and said clutch is automatically engaged and disengaged by rocking movement of a lever in the operation of the machine.

My improved attachment for cutting and holding the thread is adapted for automatic operation in combination with various of the movable parts referred to in the Reece type of machine or with similarly movable parts in other types of machine.

As the construction and operation of the Reece machine is well understood in the art, I have shown in the drawings only such parts thereof as are directly associated with the operation of my attachment.

Referring to the drawings, 1 is the stationary bed of the machine and 2 is the carriage or frame, which, in the operation of the machine in stitching a buttonhole, moves first in the direction of the arrow, 3, in Fig. 1, and then in a reverse direction, the means for moving said frame not being shown. This frame carries the stitch-forming mechanism, which is operated in the usual manner.

The needle-bar, 4, has the usual vertical reciprocating motion, and is rotated at certain times by means of a pinion, 5, thereon engaged by a gear-rack, 6, fixed upon the upright rocker-post, 7, to which a rocking motion is at certain times imparted in the operation of the machine.

The engagement and disengagement of the clutch, whereby the needle-operating shaft is driven from the main shaft, is accomplished by means of a rock-lever, 8, actuated in one direction by a coil-spring, 9, and in the opposite direction by a movable pin or plunger, 10, which at certain times in the operation of the machine is forced upward against the lower end of said lever. For an understanding of the present invention, it will be sufficient to state that the pin, 10, is automatically thrust upward to rock the lever, 8, at the beginning of the stitching of the buttonhole; and said pin, 10, is automatically depressed at the completion of the stitching of the buttonhole, permitting the spring, 9, to impart a return rocking movement to the lever, 8, said lever, 8, also par-

taking of the back and forth movement of the frame, 2; and that during the period from the time that the pin, 10, is depressed until it is again forced upward, the vertical 5 reciprocating movement of the needle 4^a is discontinued and the movable frame is moved forward to cutting position and returned to the position for beginning the next button-hole; and at about the middle of the stitching 10 operation of the needle, the needle-bar is rotated by rotative movement of the post, 7, in a clockwise direction; and during the period while the stitching movement of the needle is discontinued, the needle-bar is rotated in the opposite direction by a reverse 15 rotative movement of the post, 7.

My attachment comprises a rocker-arm, 11, fixed upon the rocker-post, 7; a cutter-releasing arm, 12, mounted upon the lower 20 end of the lever, 8; a plate, 13, attached to the bed of the machine by screws, 14, and various parts mounted upon said plates, 13.

Secured upon the plate, 13, by screws, 15, is a slideway, 16, for a slide-plate, 17, which 25 is adapted to reciprocate through said slideway parallel with the line of the buttonhole. Pivottally connected at 18, with the rear end of said slide-plate, 17, is a lever, 19, fulcrumed at 20, upon a bracket 21, projecting 30 from the slideway, 16; and upon the upper end of said lever, 19, is a latch, 19^a, pivoted at 22, upon the lever, 19, and yieldingly held by a spring, 23, against a stop, 24, on said lever, 19. Said latch, 19^a, is thus supported 35 in the path of the rocker-arm, 11, as the same is swung back and forth in partaking of the rocking movement of the post, 7, said latch being adapted to yield to permit the free passage of the arm, 11, in its movement 40 toward the front end of the machine; but it is adapted to resist the movement of said arm, 11, in a rearward direction, whereby it causes said rearward movement of the arm, 11, to rock the lever, 19, to force the 45 slide, 17, toward the front end of the machine, that is, toward the left as seen in Fig. 2. This rocking movement of the lever, 19, brings the upper end of the lever, 19, and latch, 19^a, below the level of the arm, 50 11, permitting the arm to finally pass over and beyond the latch, as shown in Fig. 2. As soon as the arm, 11, passes the latch, 19^a, in its rearward movement, the slide, 17, is automatically restored to its rearmost position by means of a coil-spring, 25, attached 55 at one end to said slide and at its other end to the bed of the machine. The slide, 17, has an L-shaped extension, 26, on its forward end, which projects inward to a point about 60 opposite the needle; and on the inner end of said extension, 26, is a slideway, 27, for the cutter-plate, 28, which carries the cutter, 29, and thread-holder, 30. The cutter-plate, 28, is connected by a post, 31, which projects 65 up through a slot, 32, in the slide-extension,

26, with a plate, 33, above the slide-extension and parallel therewith. A coil-spring, 34, connected at one end to a pin, 35, on the plate, 33, and at the other end to one of the posts, 36, through which the plate, 33, slides, 70 tends to draw the plate, 33, and the cutter-plate, 28, outward, toward the right as viewed in Fig. 4, in a direction to cause the cutter, 29, to sever the thread. During the intervals between successive operations of the thread-cutter, the plate, 33, and the cutter-plate, 28, are held in their innermost position, against the force of the spring, 34, and with the cutter open, by means of a keeper, 37, pivoted at 38, upon the slide, 17, which 75 keeper is yieldingly held by a spring, 39, against a stop 44, with its upturned end in the path of the plate, 33, as shown in Figs. 4, 5 and 8. When the keeper, 37, is moved out of the path of the plate, 33, said plate is 80 quickly moved outward by the spring, 34, to actuate the cutter.

In the operation of the machine, the cutter is automatically opened, and the plate, 33, forced to its innermost position, by means 85 of a cam-plate, 40, fixed upon the plate, 13, in the path of a stud, 41, carried by the plate, 33, and adapted to be engaged thereby as the plate, 33, and stud, 41, are moved forward in accordance with the forward 90 movement of the slide, 17, upon which they are mounted. When thus moved to the position shown in Fig. 4, the cutter will be opened and the keeper, 37, will be forced by its spring, 39, against the stop, 44, with 100 its upturned end opposite the end of the plate, 33, and will thereafter serve to retain the plate, 33, in its innermost position with the cutter open until the keeper, 37, is again forced out of the path of the plate, 33. At 105 the proper time for cutting the thread, the keeper, 37, is released by the engagement therewith of the offset-end, 42, of the arm, 12, due to the forward movement of the lever, 8, accompanying the movable frame, 110 2, after the lower end of the lever, 8, has been released to the action of its spring, 9, by the downward withdrawal of the pin, 10. The thread-cutter, 29, extends transversely 110 of the cutter-plate, 28, leaving, when the cutter is open, an opening or notch, 43, into which the thread is drawn by the needle, from the work, 45, as the movable frame, 2, moves forward from its position at the end of the buttonhole-stitching operation to the 115 buttonhole-cutting position; and at about the time the movable frame reaches the cutting position, the arm, 12, releases the keeper, 37, to actuate the thread-cutter. The thread-holder, 30, projects slightly in advance 120 of the cutter, 29, and when the keeper 37, is released, the thread-holder, 30, first draws and binds the thread under the end of the slide-extension, 26, just before the cutter coöperates with the bottom wall of 125 130

the slideway, 27, to cut the thread. Just before the stitching of the next buttonhole is begun, the rocker-post, 7, operates to rotate the needle-bar and at the same time moves the arm, 11, rearward against, and past, the latch, 19^a, imparting a forward movement to the slide, 17, its extension, 26, and the cutter and other parts carried thereby, which forward movement by engagement of the stud, 41, with the cam, 40, opens the cutter and holder to release the end of the thread, and locks the cutter open by means of the keeper, 37, as above explained.

In Fig. 1 the parts are shown with the movable frame, 2, in the buttonhole-cutting position, just after the cutter has been released by the keeper, 37, and actuated by its spring, 34. The plate, 33, is reduced in width at the end which engages the keeper, 37, to permit the cutter to be released by a comparatively short movement of the keeper.

In Figs. 2 and 4, the arm, 11, is shown as just passing the latch, 19^a, the cutter having been forced open by engagement of the stud, 41, with the cam, 40, the cutter being at this time located somewhat forward of the position which it occupies for cutting the thread.

What I claim as new and desire to secure by Letters Patent is—

30 1. In a machine of the class described, and in combination, a bed; stitch-forming mechanism, comprising in part a thread-carrying member; a slide capable of to-and-fro movement and having a slideway at right angles to the line of said movement; a cutter-plate movable in said slideway at right angles to the line of movement of said slide having a cutter adapted to engage a thread extending between the work and said thread-carrying member; a spring for actuating said cutter-plate in a direction to cut the thread; an automatically engaging keeper for retaining the cutter in its open position against the force of said spring; means for moving said slide to-and-fro; means actuated by movement of said slide in one direction for opening the cutter and permitting the engagement of said keeper; and means for automatically releasing said keeper.

50 2. In a machine of the class described, and in combination, a bed; stitch-forming mechanism, comprising in part a thread-carrying member; a reciprocatory plate; a cutter movably mounted on said plate and carried thereby, said cutter being adapted to engage a thread extending between the work and said thread-carrying member; a spring for closing said cutter to sever the thread; an automatically engaging keeper for holding said cutter open against the force of said spring; a cam-follower connected with said cutter; a cam-plate in the path of said cam-follower adapted to be engaged thereby when said reciprocatory plate is moved in one direction, to open the cutter and permit

the engagement of said keeper; means for reciprocating said reciprocatory plate; and means for automatically releasing said keeper.

3. In a machine of the class described, and in combination, a bed; stitch-forming mechanism, comprising in part a thread-carrying member; a slide capable of to-and-fro movement and having a slideway at right angles to the line of said movement; a cutter-plate movable in said slideway at right angles to the line of movement of said slide, having a cutter adapted to engage a thread extending between the work and said thread-carrying member; a spring for actuating said cutter-plate in a direction to cut the thread; an automatically engaging keeper for retaining the cutter in open position against the force of said spring; means for moving said slide to-and-fro; a cam-follower connected with said cutter-plate; a cam-plate in the path of said cam-follower adapted to be engaged thereby when said slide is moved in one direction, to open the cutter and permit the engagement of said keeper; and means for automatically releasing said keeper.

4. In a machine of the class described, and in combination, a bed; stitch-forming mechanism, comprising in part a thread-carrying member; a reciprocatory plate; a cutter movably mounted on said plate and carried thereby, said cutter being adapted to engage a thread extending between the work and said thread-carrying member; a spring for closing said cutter to sever the thread; an automatically engaging keeper for holding said cutter open against the force of said spring; a cam-follower connected with said cutter; a cam-plate in the path of said cam-follower adapted to be engaged thereby when said reciprocatory plate is moved in one direction, to open the cutter and permit the engagement of said keeper; a lever connected with said reciprocatory plate whereby said plate can be moved in the direction to open the cutter; a spring for moving said reciprocatory member in the opposite direction; a rocker-arm adapted at certain times to engage said lever and thereby move said reciprocatory member against the force of its actuated spring; and a rocker-arm adapted at certain times to automatically engage and release said keeper.

5. In a buttonhole-sewing machine of the class described, and in combination, a stationary bed; a frame movable to-and-fro upon said bed; stitch-forming mechanism carried by said movable frame including a rotatively mounted vertically reciprocatory needle-bar and needle, an upright rocker-post, operatively connected with the needle-bar to rotate the same, and a lever whereby the vertical reciprocating movement of the needle is automatically started at the beginning of the stitching of a buttonhole and

- automatically stopped at the end of the stitching thereof, said frame being automatically moved forward and back and said rocker-post being automatically rocked in 5 one direction during the interval when the needle is idle and said rocker-post being automatically rocked in the opposite direction during the stitching operation of the needle; a slideway mounted upon said bed; 10 a slide movable in said slideway parallel with the line of the buttonhole; a cutter movably mounted on said slide adapted to engage a thread carried by said needle during the forward movement of said frame, while the vertical reciprocating movement of said needle is discontinued; a spring for closing said cutter to sever the thread; an automatically engaging keeper for holding said cutter open against the force of said spring; a cam- 15 follower connected with said cutter; a cam-plate in the path of said cam-follower adapted to be engaged thereby when said slide is moved forward, to open the cutter and permit the engagement of said keeper; a rocker- 20 arm fixed upon said rocker-post; a lever connected with said slide adapted to be engaged by said rocker-arm to impart a forward movement to said slide; a spring for imparting a return movement to said slide; 25 and an arm mounted upon said first mentioned lever and adapted by the resultant needle-stopping movement thereof and forward movement of said frame to release said keeper. 30 6. In a machine of the class described, and in combination, a stationary bed; a frame movable to-and-fro upon said bed; stitching-forming mechanism carried by said movable frame including a rotatively mounted ver- 35 tically reciprocatory needle-bar and needle, an upright rocker-post operatively connected with the needle-bar to rotate the same, and a lever whereby the vertical reciprocating movement of the needle is automatically 40 started at the beginning of the stitching of 45 a buttonhole and automatically stopped at the end of the stitching thereof, said frame being adapted to be moved forward and back, and said rocker-post being automatically rocked in one direction during the 50 interval when the needle is idle and said rocker-post being automatically rocked in the opposite direction during the stitching operation of the needle; a slideway mounted upon said bed; a slide movable in said slide- 55 way parallel with the line of the button- hole, said slide having on its front-end a slideway at right angles to its line of movement; a cutter-plate reciprocatory in said slideway on said slide and having a cutter 60 adapted to engage a thread carried by said needle, during the forward movement of said frame, while the vertically reciprocating movement of said needle is discontinued; a spring for moving said cutter-plate in a 65 direction to close the cutter and cut the thread; an automatically engaging keeper for holding said cutter open against the force of said spring; a cam-follower connected with said cutter-plate; a cam-plate 70 in the path of said cam-follower adapted to be engaged thereby when said slide is moved forward to open the cutter and permit the engagement of said keeper; a rocker-arm fixed upon said rocker-post; a lever connected with said slide adapted to be engaged by said rocker-arm to impart a forward movement to said slide; a spring for im- 75 parting a return movement to said slide; and an arm mounted upon said first mentioned lever and adapted by the resultant needle-stopping movement thereof and forward movement of said frame to release said keeper. 80 85 In testimony whereof, I have hereunto set my hand this 20th day of September, 1912.
